UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

ROCK DRILL.

Application filed April 22, 1926. Serial No. 103,904.

This invention relates to rock drills, but more particularly to a valve bushing for the distributing valve of fluid actuated rock drills.

5 The objects of the invention are to enable an oscillatory distributing valve of the plate type to be suitably mounted in a cylindrical valve chamber, to protect the valve chest against wear, to reduce the number of parts 10 of the rock drill, and to hold the valve bushing and valve seat in the valve chamber in an improved and simplified manner.

Other objects will be in part obvious and in part pointed out hereinafter.

15 The invention consists of the combination of elements and arrangement of parts substantially as hereinafter described and more particularly pointed out in the appended claims and illustrated in the accompanying drawings, in which—

Figure 1 is an elevation, in section, of so much of a rock drill as will serve to illustrate the invention and showing the valve and the piston in one position,

25 Figure 2 is a view similar to Figure 1 showing the valve and the piston in another position,

Figure 3 is a transverse view taken through Figure 1 on the line 3—3 looking 30 in the direction of the arrows, and

Figure 4 is a transverse view through Figure 1 on the line 4—4 looking in the direction of the arrows.

Referring to the drawings, the invention 35 is shown embodied in a rock drill having a cylinder A provided with a free exhaust port B. Within the cylinder A is a reciprocating hammer piston C having a forward extension or nose D. In this instance the cylinder A is sealed at its front end by a front cylinder washer E which receives slidably 40 the nose D of the piston C and the rearward end of the cylinder is provided with a closure in the form of a back cylinder washer F.

45 The parts comprising the casing of the rock drill, namely, the cylinder A, the front cylinder washer E and the back cylinder washer F are held together by the usual side bolts F'. The parts so far described are 50 shown merely for illustrative purposes, and the back cylinder washer F is shown solid for the sake of simplicity of illustration. It is to be understood, however, that the usual rotation mechanism may be provided 55 to extend through the back cylinder washer

F to cooperate with the piston C and the usual chuck parts (not shown) for imparting rotative movement to a drill steel (not shown) against which the hammer piston C is adapted to strike.

60 In accordance with the present invention, a valve chest G preferably formed integrally with the cylinder A, and longitudinally thereof, is provided with a cylindrical valve chamber H closed at one end by a wall J 65 forming an integral part with the valve chest G.

Pressure fluid for operating the percussive element of the drill may be conveyed from a suitable source of supply to a connection K 70 in the valve chest G from whence it may pass through passages L and O branching from the connection K and inclined towards the rearward and forward ends respectively of the chamber H. Passages P and Q lead 75 from the valve chamber H to the rearward and front ends respectively of the cylinder A.

Within the chamber H, in this instance, is arranged a bushing R recessed intermediate its ends as at S to form a flat seating surface T which serves as a seat for a flat plate valve U. The plate valve U is substantially like the valve described in my copending United States application, Serial 85 No. 69,954 entitled Rock drill, and a detailed description of the valve will therefore be omitted in the present application.

The bushing R is preferably of generally cylindrical formation and is provided at its 90 inner end with a cylindrical portion V which cooperates slidably with the wall forming the chamber H. A somewhat similar cylindrical portion W forms a seal near the outer end of the bushing and a flange 95 X on the portion W is seated in recess Y in the outer end of the chamber H and is of such length that it projects a slight distance beyond the end of the valve chest. The intermediate portion Z of the bushing R is 100 preferably of semi-cylindrical cross sectional area to contact snugly with the wall of the chamber H and has a transverse semi-cylindrical slot b to register with a similar slot c in the valve for the reception of a 105 pin d which forms a pivot for the valve U. The pin d is preferably of a length corresponding to the diameter of the chamber H so that the said pin will be held against endwise movement by the walls of the chamber. 110

Passages *e* and *f* formed in the rearward and front ends of the portion *Z* register with the passages *P* and *Q* and are controlled by the valve *U*.

5 Suitable means are provided for holding the bushing *R* securely against endwise movement and also against rotation within the chamber *H*. To this end a notch *g* is formed in the flange *X* to cooperate with 10 the front cylinder washer *E* whereby the bushing is forced or held in the chamber *H*.

In assembling the device, the pin *d* may be inserted in the slot *b* and the valve may then be seated on the pin *d*. With the parts 15 in this position, the bushing *R* may be inserted into the chamber *H* and the front cylinder washer *E* may then be placed in position to bear against the end of the bushing. Thereafter the side bolts *F* may be 20 placed in position and the parts comprising the casing of the drill may be drawn firmly together, thus holding the bushing *R* securely within the chamber *H*.

I claim:

25 1. In a fluid actuated rock drill, the combination of a cylinder, a valve chest on the cylinder having a valve chamber, a bushing in the chamber and projecting from one end thereof, and a front cylinder washer for the cylinder engaging the bushing to hold said bushing against rotative and longitudinal movement in the chamber.

2. In a fluid actuated rock drill, the combination of a cylinder, a valve chest on the 35 cylinder having a valve chamber, a bushing in the chamber projecting at one end thereof, said bushing having a notch at one end, and a front cylinder washer at the end of

the cylinder engaging the notch for preventing rotative and longitudinal movement of 40 the bushing in the chamber.

3. In a fluid actuated rock drill, the combination of a cylinder, a valve chest on the cylinder having a cylindrical chamber open at only one end, a bushing insertable through 45 the open end of the chamber comprising end portions to cooperate with the walls of the chamber and an intermediate partly circular portion with a flat surface to form a valve seat, one of said end portions projecting 50 from the chamber and having a notch, and a front cylinder washer cooperating with the notch for holding the bushing against rotative and longitudinal movement in the chamber.

4. In a fluid actuated rock drill, the combination of a cylinder, a valve chest on the cylinder having a cylindrical chamber open only at its forward end, a bushing insertable through the front end of the chamber and extending throughout the length of the chamber, cylindrical end portions on the bushing cooperating with the walls of the chamber one of said end portions projecting 60 from the chamber and having a notch, said bushing having an intermediate semi-cylindrical portion with a flat surface forming a valve seat, and a front cylinder washer at the end of the cylinder to engage the notch in the bushing for holding said 65 bushing against rotative and longitudinal movement in the chamber.

In testimony whereof I have signed this specification.

CHARLES C. HANSEN.
